(57) **CLAIM**

The ornamental design for an abdominal binder, as shown and described.

DESCRIPTION

FIG. 1 is a front and top perspective view of an abdominal binder, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an enlarged top plan view thereof;

FIG. 7 is an enlarged bottom plan view thereof;

FIG. 8 is an enlarged view of a portion indicated with numeric **8** in FIG. 1; and,

FIG. 9 is an enlarged view of a portion indicated with numeric **9** in FIG. 1.

The broken lines in the figures illustrate portions of the abdominal binder that form no part of the claimed design. The dash dot dash lines in FIGS. 1, 8 and 9 are for the purpose of depicting the boundary lines of the enlarged views and form no part of the claimed design.
